Philip H. Case,

UNITED STATES PATENT OFFICE.

PHILIP H. CASE, OF ALEXANDRIA, MINNESOTA, ASSIGNOR OF ONE-HALF
TO ROBERT J. MCNEIL, OF SAME PLACE.

HARNESS-PAD.

SPECIFICATION forming part of Letters Patent No. 257,209, dated May 2, 1882.

Application filed February 11, 1882. (No model.)

To all whom it may concern:

Be it known that I, PHILIP H. CASE, a citizen of the United States, residing at Alexandria, in the county of Douglas and State of Minnesota, have invented a new and useful 5 Harness-Pad, of which the following is a specification.

My invention relates to improvements in harness-pads by the use of a combination burr-plate composed of metal and leather; and the 10 objects of my improvements are, first, to form a stiff center to the pad over the backbone of the draft-animal; second, to make the pad self-adjustable to the form of any animal upon which 15 it may be used, thereby avoiding chafing or galling the animal and equalizing the bearing of the pad upon the animal's back upon each side of the backbone. I attain these objects by the mechanism illustrated in the accompanying drawings, in which—

Figure 1 is a lateral view of the entire pad, and Fig. 2 a bottom view of the burr-plate.

Similar letters refer to similar parts throughout the two views.

Sections *a* and *b* of Fig. 1 represent what is called the "back-band," and is composed of two pieces of leather stitched together. Section *e* is a housing attached to the back-band *a b*, and, being somewhat broader than 25 the back-band, projects beyond it.

Sections *d* and *e* compose the burr or nut plate, of which section *d* is of leather and *e* of metal, secured together by rivets or bolts, (shown at each end of the metal plate *e* by letters *j j*.) *f* denotes the outline of the cushion. It is firmly secured to the leather plate *d*, and is stuffed with hair or other soft and suitable material. 35

The cushion is of leather. The burrs or nuts *i i i i* are firmly fixed in the leather plate *d*, to receive the pad-screws *h h* and the terret-screws *g g*. These screws pass through the several sections of the pad and hold them firmly together. 40

Having fully described my invention, what 45 I desire to claim and secure by Letters Patent is—

In a harness-pad, the burr or nut plate composed of the upper leather section, *d*, provided with the burrs or nuts *i*, and the metal plate *e*, 50 riveted to the under surface of the leather section, all substantially as and for the purpose stated.

PHILIP H. CASE.
